UNITED STATES PATENT OFFICE.

STEWART ROY ILLINGWORTH, OF BRYN FEDWEN, RADYR, WALES, ASSIGNEE TO ILLINGWORTH CARBONIZATION COMPANY, LIMITED, OF MANCHESTER, ENGLAND.

PLANT FOR THE CARBONIZATION OF COAL.

Application filed June 11, 1923. Serial No. 644,750.

To all whom it may concern:

Be it known that I, STEWART ROY ILLINGWORTH, a subject of the King of Great Britain, residing at Bryn Fedwen, Radyr, Glamorganshire, Wales, have invented new and useful Improvements in Plants for the Carbonization of Coal, of which the following is a specification.

The object of this invention is to provide an improved plant for the carbonization of coal, which shall be especially suitable for use in processes described in my earlier Patents Nos. 1,422,269 and 1,445,954 and 1,462,576.

Coals which are particularly adapted for use with the improved plant are coals which have been subjected to a preliminary treatment as described in the specifications Nos. 1,422,269 and 1,462,576, blended coals such as described in the specification No. 1,445,954, and some natural coals, which coals do not expand on carbonization.

By this plant I am enabled to form fuel of definite shape and size.

According to my invention I provide in a long horizontal or inclined retort an endless chain which can be driven by vertical sprocket wheels and I mount on this chain a number of trays each of which is divided by partitions into a number of compartments forming moulds, of the size which the briquettes or blocks of fuel are to have, and I provide at one end of this retort means for feeding coal on to the trays.

At the end of the retort opposite to the end where the coal is fed I provide a retort into which the trays deliver their contents.

The trays are turned over and the briquettes drop out of them into the oven or retort. The trays are preferably tapered in order to facilitate discharge.

Carbonization proceeds from the sides of the coal in each mould towards the middle and consequently the outer shell of each piece or block of coal becomes heated sooner than does the centre. Consequently it is only necessary to make the first retort long enough and to cause the trays to travel through it at such a rate that this outer shell may be sufficient to prevent fracture of the block or briquette as it falls from the tray into the oven. I have found that such formation of the shell occurs after about one fifth of the whole time required for complete conversion into smokeless fuel and

therefore the oven may be made of a sufficient size to take a charge four times as great as the charge of the first retort.

The coal is preferably fed to the trays by a star feed valve from a hopper. This star valve should be of the full width of the trays and is so geared to the sprocket which drives the chain that it delivers coal as each tray passes beneath it.

In order to prevent waste of coal the back of each tray is preferably caused to overlap the front of the tray following it.

I may also provide a scraper which levels the coal as the trays pass beneath it, and a plate may be fixed above the trays with sufficient clearance to allow them to pass, which plate ensures that the upper surfaces of the briquettes are smooth.

If it is desired to preheat the coal as described in my earlier specifications in the same plant, the preheater may be arranged above the horizontal retort and the waste gases may be led from the flues of the horizontal retort and may be employed to heat this preliminary retort.

The process described in this case is claimed in my companion application Serial No. 644,749, filed June 11, 1923.

The accompanying drawings illustrate plant made in accordance with this invention.

Figures 1, 1^a and 1^b show a longitudinal section of a carbonizing plant, Figure 1^a being an extension of the upper left hand portion of Figure 1, and Figure 1^b a downward extension of the right hand portion of Figure 1.

Figures 2 and 2^a show a longitudinal section through the same, Figure 2^a being a downward extension of Figure 2.

Figures 3 and 3^a show a longitudinal section of the carbonizing plant of the previous figures combined with a preheating cylinder.

Figure 4 is a transverse section of the same, taken on the line 4—4 of Figure 3^a.

Figure 5 is a vertical sectional view on the lines 5—5 and 6—6 of Figure 1.

10 is a horizontal muffle retort in which are mounted pairs of sprocket wheels 11 and 12 over which pass two endless chains 13, 10^a rollers 131 being provided to assist in the running of the chains. On the chains 13 are mounted trays 14 which are divided by partitions 141 into a number of compartments forming moulds of the size which the bri-

quettes are to have. At one end of the retort 10 is a hopper 15 provided with a feeding and measuring wheel 151 by which coal is supplied to the moulds, and a scraper 152 is provided to level the top surface of the coal in the trays.

The trays 14 have flanges 142 on their rear ends which overlap the front ends of the adjacent trays, so preventing the waste of coal.

10 At the end of the retort 10 remote from the feeding apparatus 15 is a vertical retort 16 provided at its base with a baffle plate 17 and a star wheel 18 by means of which a measured quantity of material is delivered from the retort 16. It will be observed by reference to Figures 1^b and 2^a that the star wheel 18 consists of a plurality of sets of arms, each set as shown consisting of four arms and as shown in Figure 2^a there are five parallel series of such sets of arms though this number is not essential. The sets of arms have spaces between them as shown in Figure 2. Prongs 16^a which are rigidly held at their inner ends have free outer or lower ends which extend between the sets of arms of the star wheel. In this way the delivery of the briquettes from the retort 16 is regulated. On the rotation of the star wheel the material delivered falls into one or other of the cooling chambers 19 or 20 according to the position of the guide 181. The cooling chambers are provided with doors 191 and 201 through which the material is delivered. The retort 10 is heated by gas burners in horizontal passages 21 whilst the retort 16 is heated by burners in horizontal flues 22 and at the base of the retort 16 is a pipe 23 for the admission of gas. The retort 10 is provided with inspection doors 101 and 102 and a main 103 through which the gaseous products are extracted.

The retort 10 is surrounded by a casing or jacket C between which and the retort 10 there is an annular chamber D into which the products of combustion from the flues 21 pass by means of the ports d and from this chamber D the products of combustion escape through a stack or chimney E.

The retort 16 is surrounded by a casing or jacket F and gas and air or other fuel enters at X and passes into a flue or passage G which communicates through ports g with the flues 22 which are annular and which deliver through ports H to a flue K which in turn delivers to the chamber D communicating by means of ports d' with the flues 21. The manner in which the fuel enters the flues 22 and passes therefrom to the chamber D and into the flues 21 and out from these flues to the stack as indicated by the arrows. Suitable dampers may be employed at x and y as indicated.

In operation the trays 13 in the retort 10 are caused to travel through it at such a rate that the outer shell of a briquette is sufficiently hard to prevent fracture when the

briquette is dropped by the reversal of the trays 13 into the retort 16. It is found that the formation of the shell occurs about one fifth of the whole time required for complete conversion into smokeless fuel, therefore, the 70 furnace 16 is of sufficient size to take four times as great a charge as the retort 10, and the star wheel 18 is driven at such a pace that the charge is extracted from the retort when it is sufficiently carbonized. The charge 75 then falls into one or other of the cooling vessels 19 or 20. In the manufacture of smokeless fuel the heat of the two retorts 10 and 16 is from 500° to 600° C. but in the manufacture of metallurgical coke in which a large output of liquid byproducts is required the furnace 10 is maintained at about 500° to 600° C. whilst the top of the retort 16 is maintained at 600° C. and the bottom at 900° to 1000° C. In this case the retort 16 must be of a capacity from 7 to 8 times that of the retort 10.

The furnaces 10 and 16 and the cooling chambers 19 and 20 may be jacketed and may be used for heating gas given off by the coals which may be led to the pipe 23 from which it passes to the retort 16 and then to the retort 10.

Referring to Figures 3 and 4, 24 is an iron cylinder mounted in a chamber 25 of refractory material which is heated by horizontal flues 251. The flues 251 are provided with burners 252 which supply fuel to the flues 251 and the flames from the burners are shielded from the retort 24 as indicated at 253. The flues 251 are in communication with passages 171 which deliver to the chamber 25. Fuel also passes to the chamber 25 from the flues 101 and is boosted by the gases passing from the passages 171. After passing around the retort 24 the gases pass out through a suitable chimney. In the preheating cylinder 24 is a shaft 26 driven by gearing at its left hand end, and on the shaft 26 are blades 262 so inclined that the coal in the cylinder is turned over and caused to travel a definite amount through the cylinder. At the left hand end also is a feed hopper 27 provided with a measuring valve 271 which is driven from the shaft 26 at a speed which will introduce sufficient coal into the preheating cylinder 24. On the shaft 26 is a worm wheel 261 driven by a worm 260 and on the shaft 272 of the valve 271 is a worm wheel 273 driven by a worm 274, and on the shafts of the worms 260 and 274 are sprocket wheels 263 and 275 driven by a chain 30, the valve 151 being similarly driven from the shaft of the sprocket wheel 11. At the right hand end of the cylinder 24 are crushing rollers 28 which are driven in conjunction with a valve 29 by gearing from the shaft 26.

The term "retort" in the claims includes 125 muffles, ovens, or the like. 130

The method or process herein described means for retaining the material in said is not claimed herein as it is claimed in my larger retort until the coking operation is application No. 644,749 filed June 11, 1923. completed.

It will be observed that the coal while being fed from the retort 10 is divided into discrete masses in the molds 14, and these masses are continuously passed through a zone maintained at such temperature that the masses are partially carbonized or partially coked, a hard shell being formed around each mass and that these shell covered masses are then passed into a zone of larger dimensions than that first mentioned in the retort 16 which is heated to a coking temperature, the shell covered masses being passed through the second zone at a slower rate than the rate at which they traversed the first zone. In this way I am able to rapidly coke the outside of the masses and to complete the carbonizing operation more slowly in retort charges of relatively large dimensions.

What I claim is:—

1. A plant for the carbonization of coal comprising a retort, a conveyor therein, a series of molds supported on the conveyor, means for continuously operating the conveyor, means for supplying coal to the molds, means for heating the retort to effect the partial carbonisation of coal in the molds, a second retort to which the molds deliver the partially coked material and which is of materially larger dimensions than the first retort, means for heating the second retort, and means for discharging the material from the second retort.

2. A plant for the carbonization of coal comprising a horizontal retort, a conveyor therein, a series of molds supported on the conveyor, means for continuously operating the conveyor, means for supplying coal in measured quantities to the molds, means for heating the retort to a suitable temperature to form hard shells on the coal in the mold as they pass through the retort, a second retort to which the material is delivered from the molds and which is of materially larger area than the retort first mentioned, means for heating said larger retort and means for retaining the material in said larger retort until the coking operation is completed.

3. A plant for the carbonization of coal, comprising a horizontal retort, a conveyor therein, a series of molds supported on the conveyor, means for continuously operating the conveyor, means for supplying coal to the molds, means for heating the retort to a suitable temperature to form hard shells on the coal in the molds as they pass through the retort, a second retort to which the material is delivered from the molds and which is of materially larger area than the retort first mentioned, means for heating said larger retort to a higher temperature than the heat of the first mentioned retort and

4. A plant for the carbonization of coal comprising a horizontal retort, a horizontally arranged conveyor therein, a series of molds supported on the conveyor having flanges overlapping adjacent molds, means for operating the conveyor, means for supplying coal to the molds, means for heating the retort and means for delivering material from the molds when sufficiently treated.

5. A plant for the carbonization of coal comprising a retort, a conveyor therein, a series of molds supported on the conveyor, means for operating the conveyor, means for supplying coal to the molds, means for heating the retort to a suitable temperature to form hard shells on the coal in the molds as they are passed through the retort, a second retort to which the material is delivered from the molds and which is of materially larger area than the retort first mentioned, means for heating said larger retort, a rotary star wheel gate or valve controlling the delivery of material from the larger retort and prongs cooperating with said star wheel valve which assist in controlling the delivery of the material from said last retort.

6. A plant for the carbonization of coal comprising a horizontal retort, a conveyor therein, a series of molds supported on the conveyor, means for operating the conveyor, a preheating retort above the retort first mentioned, means for supplying coal to one end of said preheating retort, means for delivering preheated material from the opposite end of said retort to the molds on the conveyor in the first mentioned retort, a retort to which the molds deliver and means for heating said last mentioned retort to complete the carbonizing of the material.

7. A plant for the carbonization of coal comprising a horizontal retort, a conveyor therein, a series of molds supported on the conveyor, means for operating the conveyor, a preheating retort above the retort first mentioned, means for supplying coal to one end of said preheating retort, means for delivering preheated material from the opposite end of said retort to the molds on the conveyor in the first mentioned retort, a retort to which the molds deliver, means for heating said last mentioned retort, heating flues for the conveyor containing retort heating flues for the preheater which communicate with the flues of the conveyor containing retort, and burners in the flues for the preheating retort which are shielded from said retort.

In testimony that I claim the foregoing as my invention I have signed my name this twenty-ninth day of May, 1923.

STEWART ROY ILLINGWORTH,
